UNITED STATES PATENT OFFICE.

ALBEN E. LUNDELL, OF NEW YORK, N. Y., ASSIGNOR, BY MESNE ASSIGNMENTS, TO
WESTERN ELECTRIC COMPANY, INCORPORATED, A CORPORATION OF NEW YORK.

AUTOMATIC TELEPHONE SYSTEM.

1,233,891.

Specification of Letters Patent. Patented July 17, 1917.

Application filed October 4, 1915. Serial No. 53,979.

To all whom it may concern:

Be it known that I, ALBEN E. LUNDELL, a citizen of the United States, residing at New York, in the county of Bronx and State 5 of New York, have invented certain new and useful Improvements in Automatic Telephone Systems, of which the following is a full, clear, concise, and exact description.

10 This invention relates to telephone exchange systems employing trunk-hunting switches of the step-by-step type, and particularly to such systems wherein the switches are driven over the trunk terminals 15 from a common interrupter. It has been found in practice that where a number of trunk-hunting switches are stepped over multiple trunk terminals by impulses from a common interrupter that a number of such 20 switches may test multiples of the same trunk at the same time, since they are stepping over such multiples in synchronism. This may result in the same trunk being seized by a number of switches.

25 It is the object of this invention to provide a circuit arrangement wherein this difficulty is avoided, and wherein such interrupter operates only when necessary, that is to say, when a trunk-hunting switch is in the trunk- 30 hunting position.

In accordance with this invention, the trunks are multiplied in groups to groups of selectors, and the interrupter for stepping the selectors comprises a series or string of 35 relays. Each relay has a contact adapted to be included in circuit with the stepping magnets of one of the selectors of each of the aforesaid groups of selectors, no two of which selectors have access to the same 40 trunk group. When any selector goes into the trunk-hunting position, a starting relay is energized and causes the series of relays to energize successively until a predetermined relay of the string is reached, which 45 unlocks the string and causes them to begin locking up again. This operation continues as long as the starting relay remains energized, which will be as long as there are 50 selectors in the trunk-hunting position, the starting relay becoming deenergized and stopping the operation of the interrupter when all the switches have found idle trunks.

55 Referring to the drawing, Figure 1 is a diagram of the interrupter of this invention,

this view also showing three of the trunk-hunting switches adapted to be driven thereby; Fig. 2 is a diagram of a known selector circuit adapted to operate with the interrupter of this invention. 60

Referring to Fig. 1, c^1 designates a conductor common to, say, ten trunk-hunting switches, the stepping magnets 20, 28 of two only of which are shown. Each of these trunk-hunting switches has a set of brushes 65 21, 22, 23. Each of these sets is adapted to wipe over the trunk terminals 24, 25 and 26 of a different trunk group; that is to say, these trunk groups would not be multiples of each other. Similarly, c^2 designates a 70 conductor common to, say, ten trunk-hunting switches, each of which would have access to different groups of trunks. The group of trunk terminals t^2 , however, of one of the selectors associated with conductor c^2 75 would be multiples of the terminals 24, 25, 26 of one of the selectors associated with conductor c^1 , as shown. Relay 29 is the starting relay which is common to all the trunk-hunting switches. The invention will 80 be more readily understood from a detailed description of the operation of the system.

Referring to Fig. 2, the calling line, whose substation is designated A, may be associated with the selector shown by a line 85 finder or equivalent means, well known in the art. When the line has been thus extended, the following circuit is closed to energize stepping relay 10 at the selector: free pole of battery, right winding of relay 90 10, side-switch arm 1, conductor 11, line conductor 12, sender S, through the telephonic apparatus at substation A, line conductor 13, conductor 14, side-switch arm 2, left winding of relay 10, to ground. Relay 95 10 by attracting its armature energizes a slow relay 15. Relay 15 by attracting its armature interposes a break in the circuit of release magnet 16 of the selector and prepares a circuit for a slow relay 17. 100

The subscriber at substation A now operates his sender S to transmit impulses corresponding to the digit of the wanted line with which this selector is concerned. Each time the sender interrupts the line circuit, 105 an impulse is delivered to the primary stepping magnet 18 over the following circuit: free pole of battery, magnet 18, contact spring 30 top, armature and front contact of relay 15, armature and back contact of relay 110

10, to ground. Magnet 18 drives the brushes 21, 22, 23 in a primary direction to position the same in operative relation to the desired group of trunks. Upon the first retraction 5 of the armature of the stepping relay 10, an impulse is sent to a slow relay 17, which, by attracting its armature, energizes a magnet 19 by way of side-switch arm 4. This magnet 19 is the side-switch escapement magnet, and is constructed and arranged to release the side switch from position 1 to position 2 upon its deenergization. Relay 17 is a slow-acting relay and remains energized notwithstanding the interruptions in its circuit as the stepping relay operates. However, when the sender S restores and maintains the relay 10 energized, relay 17, after an interval, allows its armature to retract, thus opening the circuit of the escapement 15 magnet 19. The escapement magnet in retracting its armature moves the side switch into position 2 in the well-known manner to initiate the trunk-hunting operation. In position 2, side-switch arm 5 connects secondary stepping magnet 20 in circuit with the interrupter shown in Fig. 1. Referring now to Fig. 1, this circuit may be traced as follows: free pole of battery, magnet 20, side switch arm 5 and its second contact, conductor c^1 , right armature and back contact of relay a , conductor 31, relay 29 to ground. Relay 29 attracts its armature, locking itself up in series with relay a of the string over the following circuit: free pole of battery, 25 conductor 32, left armature and back contact of relay f , arm 33 of switch 4 and its first contact, armature and front contact of relay 29, relays a and 29 to ground. Relay a , by attracting its right armature opens 30 the circuit of stepping magnet 20, and by attracting its left armature closes the following circuit to energize relay b : free pole of battery, left armature and front contact of relay a , conductor 35, relay b to ground. Relay b at its left armature and front contact 35 closes a circuit to energize relay c , which in turn, by attracting its left armature, closes a circuit to energize relay d , etc. The energization of relay f opens the circuit 40 of relays a and 29. Relay a , in retracting its right armature, closes the circuit including stepping magnet 20 and relay 29. Magnet 20 gives the selector shaft another step, and relay a , in retracting its left armature, unlocks relay b , which in turn unlocks 45 relay c , etc. The retraction of the left armature of relay f again locks up relays a and 29. Relay a , by attracting its right armature, opens the circuit of stepping magnet 20, and energizes relay b . Relays c , d , e and f then energize in succession as before. Referring now to Fig. 2, while the interrupter is operating, as described, arm 4 connects the escapement magnet 19, in position 2, to the test brush 23. Idle trunks are 50

those upon whose test terminals 26 ground is present. Consequently, when the brush 23 engages a grounded test terminal 26, escapement magnet 19 becomes energized. The side switch is constructed to release its 70 arms from position 2 to position 3 upon the energization of escapement magnet 19. When the side switch goes into the third position, arm 5 in moving off its second contact opens the circuit of stepping magnet 20, thus stopping the switch. Side switch arm 5 also opens the circuit of relay 29, thus terminating the operation of the interrupter, unless one or more of the stepping magnets 75 of the selectors which may be associated with the conductors c^1 , c^2 , etc., are at this time operating. It is true that there may be a number of selectors testing in the same group at the same time: For example, brushes 80 21, 22, 23 may be testing the group to which terminals 24, 25, 26 belong, while brushes b^2 are testing multiples f^2 of such group. However, due to the circuit arrangement described, the impulses conveyed to the stepping magnets 20, 36 of such switches will 85 begin at different times since the contacts of relays a , b are closed in rotation, and consequently the testing brushes will arrive on multiples of the same trunk at different times. When the side switch moves into 90 position 3, arms 1 and 2 connect conductors 11 and 14 through to the brushes 21 and 22, thus cutting off the relay 10. The side switch in moving into position 3 closes circuit to operate a relay at the succeeding 95 selector, which in attracting its armature removes ground from test wire 27, thus rendering the seized trunk busy to other testing 100 selectors.

The release of the selector may be effected 105 in any well-known manner, as the called party may, in restoring his receiver, cause a ground to be placed on test conductor 27, which closes a circuit over test brush 23, side-switch arm 3 and off-normal contact 110 39 to the release magnet 16 of the selector, which in energizing, withdraws the pawls from the ratchets of the selector shaft, thus restoring the same. The release magnet also restores the side switch in the well-known 115 manner.

The switch 34 (Fig. 1) is for the purpose of regulating the speed of the interrupter; that is to say, the rate of impulses the interrupter delivers to the stepping magnets. 120 Arm 33 of such switch is shown in contact with the first terminal connected to the back contact of the sixth relay in the series. Consequently, it is this relay which initiates the unlocking and locking operations. When it 125 is desired to vary the rate of impulses delivered, the arm 33 is moved into engagement with the contact corresponding to the rate desired. It will be apparent that as the arm is moved from right to left the rate is 130

decreased. The switch 38 is provided to open the stepping circuit of magnet 20 in case the selector fails to find an idle trunk, this switch being opened in an extreme position of the selector brush shaft.

What is claimed is:

1. In a telephone exchange system, the combination with groups of automatic selector switches, groups of trunks multiplied to said groups of switches and stepping magnets for driving said selectors over said trunks, of an interrupter for said magnets comprising a series of relays, each having a contact included in circuit with the magnets of a number of selectors, each selector having access to a different group of trunks, means for opening and closing said contacts in rotation, and means for arresting a selector on an idle trunk.
2. In a telephone exchange system, the combination with groups of automatic selector switches, groups of trunks multiplied to said groups of switches and stepping magnets for driving said selectors over said trunks, of an interrupter for said magnets comprising a series of relays, each having a contact included in circuit with the magnets of a number of selectors equal to the number of relays in the series, each selector having access to a different group of trunks, means for opening and closing said contacts in rotation, and means for arresting a selector on an idle trunk.
3. In a telephone exchange system, the combination with groups of automatic selector switches, groups of trunks multiplied to said groups of switches and stepping magnets for said selectors, of an interrupter for said magnets comprising a series of relays, each having a contact included in circuit with the magnets of a number of selectors whose trunk terminals are non-multiples of each other, a common relay adapted to be included in circuit with any of said magnets and being adapted when energized to cause said relays to lock up in succession, the energization of a predetermined relay of the series unlocking said relays to again start a cycle of operations, and means for

deenergizing said common relay to terminate the operation of said relays.

4. In a telephone exchange system, the combination with groups of automatic selector switches, groups of trunks multiplied to said groups of switches and stepping magnets for said selectors, of an interrupter for said magnets comprising a series of relays, each having a contact included in circuit with the magnets of a number of selectors whose trunk terminals are non-multiples of each other, a common relay adapted to be included in circuit with any of said magnets and being adapted when energized to cause said relays to lock up in succession, the energization of a predetermined relay of the series unlocking said relays in succession, the unlocking of the last named relay again causing said relays to lock up successively, and means for deenergizing said common relay to terminate the operation of said relays.

5. In a telephone exchange system, the combination with groups of automatic selector switches, groups of trunks multiplied to said groups of switches, stepping magnets for said selectors, an interrupter for said magnets comprising a series of relays, each having a contact included in circuit with the magnets of a number of selectors whose terminals are non-multiples of each other, a common relay adapted to be included in circuit with any of said magnets and being adapted when energized to cause said relays to lock up in succession, the energization of a predetermined relay of the series unlocking said relays in succession, the unlocking of the last named relay again causing said relays to lock up successively, and means for varying the rate of impulses delivered to the magnets comprising a switch, the position of which determines the relay of the series which initiates the unlocking and locking operations.

In witness whereof, I hereunto subscribe my name this 29th day of September A. D., 1915.

ALBEN E. LUNDELL.
